United States Patent Office

Des. 191,149
Patented Aug. 15, 1961

191,149

AIRPLANE

J Mack Eaton, Atlanta, and William L. Hoerrner, Marietta, Ga., assignors to Lockheed Aircraft Corporation, Burbank, Calif.

Filed Feb. 26, 1960, Ser. No. 59,531

Term of patent 14 years

(Cl. D71—1)

Fig. 2

Des. 191,149

PAGE 2

FIGURE 1 is a perspective view of an airplane, showing our new design;

FIGURE 2 is a front elevational view thereof;

FIGURE 3 is a side elevational view thereof; and

FIGURE 4 is a top plan view thereof.

FIG. 5 is a bottom plan view thereof with the ends of the wings broken away for convenience of illustration.

The essential features of the design reside in the portions shown in full lines.

We claim:

The ornamental design for an airplane, as shown and described.
